UNITED STATES PATENT OFFICE.

CONSTANTINOS J. STAMATIS, OF PHILADELPHIA, PENNSYLVANIA.

CALIPERS.

1,286,824.

Specification of Letters Patent.

Patented Dec. 3, 1918.

Application filed April 12, 1918. Serial No. 228,242.

To all whom it may concern:

Be it known that I, CONSTANTINOS J. STAMATIS, a citizen of the United States, residing at 1223 N. 19th street, Philadelphia, 5 in the county of Philadelphia and State of Pennsylvania, have invented new and useful Improvements in Calipers, of which the following is a specification.

The invention relates to calipers and similar instruments, and has for an object to provide an instrument of precision for use in determining distances, thicknesses, and the like, especially in the machine shop where a tool of this character is employed 15 for the purpose of measuring lengths, thicknesses or diameters of machine parts.

Among other features, the invention comprehends calipers that may be employed as a divider, and which have parts thereof interchangeable to suit a particular piece of work which is to be measured, or in which 20 certain parts are to be divided off, as the case may be.

Ordinarily a pair of calipers may be 25 formed with ends which are curved toward each other; whereas, dividers usually are formed with pointed ends. My invention comprehends a combination of the two wherein I may have one of the ends of my 30 instrument pointed or curved, as the case may be, and whereby the instrument may be adapted for inside or outside or surface measuring.

In the further disclosure of the invention, 35 reference is to be had to the accompanying drawing, constituting a part of this specification, in which similar characters of reference denote corresponding parts in all the views, and in which—

40 Figure 1 is an elevation of the instrument.
Fig. 2 is a view looking at an edge thereof, and

Fig. 3 is a fragmentary enlarged view partly in section, showing in detail the particular form of locking structure.

45 Fig. 4 is a slightly modified form of my invention showing an adjustment feature, and

Fig. 5 is a fragmentary enlarged sectional view of the structure shown in Fig. 4.

Referring more particularly to the views, 50 10 and 11 are the legs of the calipers which are connected in any suitable manner at 12, whereby one leg will be pivoted on the

other, the leg 11 preferably ending at its 55 free end in a curved portion 13. Suitably riveted or otherwise attached to the leg 10 is a U-shaped spring clamp or locking element 14, provided with an opening 15, with the free end 16 of the locking element spaced 60 from the side of the leg 10. The extremity of the leg 10 is curved, as shown at 17 and is provided with an opening 18. A supplementary leg or prong element 19 is employed for use in connection with the leg 10, 65 and it is preferably formed of a single piece of metal curved at one end as at 20, and pointed at the other end as at 21. This supplementary element is adapted to be inserted through the opening 18 and through 70 the opening 15, the element being provided with a series of notches 22, into which the end 16 of the clamp or holder will spring, thus securing the element rigidly on the leg 10. It will be seen that the spring pressure 75 on the clamp will firmly hold the element against movement in the openings 15 and 18, and that the projecting portion of the element can be increased or decreased in length beyond the bend 17 as desired. 80

For certain kinds of work the point of the supplementary element can be employed in connection with the point of the other leg 11, or the curved part 20 of the element 85 can be used by merely reversing the element in position upon the leg 10, and having it locked by the clamp.

As mentioned heretofore, my instrument can be employed as calipers or dividers, as the case may be, and the supplementary leg 90 will be securely locked against movement when the device is in use, and can be readily removed and turned around to adapt the calipers or dividers to above purposes. It will be clear that a device of this character 95 consists of few and simple parts; cannot readily get out of order; can be cheaply manufactured, and will effectively perform the functions for which it is desired.

In Figs. 4 and 5 I disclose a modified 100 form of my invention, and in which instance the leg 11 has attached thereto a locking or clamping element 23, consisting of a single piece of metallic material bent in a substantial U-shape to provide a locking point 24 105 for locking engagement with notches 25 in a supplementary leg or prong element 26, said piece of metal being bent to form a

right-angled portion 27 which has an opening 28 therein, through which the element 26 is adapted to pass, a similar opening 29 being formed in the other end of the clamp 5 for the passage of the element 26. The clamp is secured to the leg 11 by a rivet 30 which, however, will permit the clamp to be rotated upon the leg, and it will be seen that by having the lower or main body portion 10 of the clamp bent, as shown at 31, the portion 32 of the clamp will bear against the face of the leg, and thus tend to hold the clamp stationary.

It will be seen that when my device is 15 used in connection with the clamp described, as shown in Fig. 4, that the device can be employed as a pair of dividers with the point 21 and the point 33 of the element 26, whereby when a distance is measured, the 20 slight rotation of the clamp 23 upon the leg 11 will move the point 33 toward or away from the point 21, so that accurate measurements can be obtained.

It will of course be apparent that as in 25 the construction shown in Figs. 1, 2 and 3, as well as in the modification shown, the removal of the supplementary leg or prong element 19 or 26, out of locked engagement with the particular clamp used therewith, is accomplished by simply turning or 30 rotating the prong element half way around, thus causing the locking end of the clamp to ride out of the notch on to the periphery 35 of the prong element, and thereby enabling the operator to slide the prong element into a new adjusted position, or entirely out of engagement with the clamp element, as the case may be.

I claim:

1. In an instrument of the character described, the combination with a plurality of pivoted legs, one of which has a curved portion provided with an opening, of a spring clamp formed with an opening and having one end connected to said leg in juxtaposition to the curved portion thereof, and a notched element slidingly passing through the opening in the curved portion of the leg and the opening in the spring clamp, with the other end of said spring clamp fitting 50 into one of the notches of the element to lock said element against movement on said leg.

2. In calipers the combination with one or more of the legs thereof, of an elongated 55 spring provided with an opening and having one end secured to the leg and the other end spaced from the leg, said spring extending longitudinally of the leg, and an element forming an auxiliary leg, said element having sliding engagement with the leg, and passing through the opening in the spring, with the spaced end of said spring normally bearing against said element.

3. In calipers the combination with one 60 or more of the legs thereof, of an element forming an auxiliary leg and in sliding engagement with one of the legs and a U-shaped spring having one end secured to the leg, said spring extending longitudinally 70 and lying to one side of the leg, with the other end of the spring spaced from the leg to normally engage with said element.

In testimony whereof I affix my signature.

CONSTANTINOS J. STAMATIS.
